UNITED STATES PATENT OFFICE

ALBERT L. ABBOTT AND WILLIAM C. MILLER, OF CANTON, OHIO, ASSIGNEES TO THE
DIEBOLD SAFE & LOCK COMPANY, OF CANTON, OHIO, A CORPORATION OF OHIO

DISAPPEARING DOOR SAFE AND THE LIKE

Application filed October 2, 1930. Serial No. 485,959.

Our invention relates to apparatus more particularly adapted for disappearing doors for structures having doorways formed in the walls or frames thereof, and doors operatively mounted for movement to and from closing position in the doorways.

In any such structure, as usually arranged, the door is hinged and swings outwardly in one direction, and either projects directly outwardly from the doorway, or if swung completely open requires space at the side of the doorway equal to the area of the door.

The space thus required for opening any usual door is waste space, and in particular when the structure is a safe, and more particularly a fire and heat resisting safe, the space requirement for opening and closing the door is very objectionable in the usual office, wherein it is necessary to utilize to the maximum efficiency all the available floor space by reason of the steadily increasing rents.

In large offices where a number of fire and heat resisting safes may be used side by side, the inconvenience and waste of space arising from the usual method of hanging safe doors is increased in direct proportion to the number of safes used, and is further increased by the fact that if the safes are placed side by side a door of one safe when swung entirely open will cover the door of another.

It has heretofore been proposed to mount the door of a safe or similar structure in such manner that the door may be shifted from a closed position to an opening position parallel to one of the sides of the structure.

Such an arrangement is inherently desirable, but the only safe of this character heretofore generally available has been very difficult to operate, requiring the use of both hands of the person opening or closing the door, and has been dangerous in use by reason of the possibility of smashing or cutting off the fingers of the person operating the disappearing door.

Moreover in the disappearing door safe heretofore available, no means have been provided for taking up the wear on the working parts which is inevitably associated with the operation of the door.

The objects of the present invention include the provision of a novel apparatus, more particularly adapted for providing a disappearing door for a safe or the like, which is simple and economical to manufacture, which may be operated if necessary by the use of only one hand of the person opening or closing the door, which embodies safety features preventing injury to the person opening or closing the door and preventing incorrect operation of the door during opening or closing thereof, and the working parts of which include adjusting means for taking up wear.

The foregoing and other objects are attained by the apparatus, structure, parts, improvements, and combinations, which comprise the present invention, and which are particularly and distinctly pointed out and set forth in the appended claims forming part hereof.

In general terms the novel apparatus of the present invention for providing a disappearing door for a safe or the like may be described as including a door frame having a doorway formed therein, a door carriage guide frame extending from one side of the door frame and angular thereto, and preferably at right angles and rearwardly therefrom, there being a door receiving opening formed in the normally front end of the guide frame, a door supporting carriage mounted for movement in the guide frame, tension means for maintaining the carriage in operative position during movement thereof, the tension means preferably comprising a flexible chain or cable connected at its ends on the carriage and guided between its ends by preferably stationary roller guide means mounted on the guide frame, a door adapted for movement to and from closing position in the doorway, preferably double hinge means mounting the door on the carriage, and releasable means engaging the door and carriage in position permitting movement of the door into the guide frame, and the door front wall preferably extending across and closing the door receiving opening of the guide frame when the door is in closed position in the doorway, and a secondary closure

90

95

100

member hinged at one side upon the door front wall and providing a closure for the door receiving opening of the guide frame during swinging of the door.

5 A preferred embodiment of the invention is illustrated in the accompanying drawings forming part hereof, in which

Figure 1 is a fragmentary top plan view, with portions in section, illustrating a safe embodying the present improved disappearing door structure or apparatus, and the door being illustrated in its closed position seated in the tongued and grooved door frame, and the other parts of the apparatus being illustrated in their respective and relative positions;

Fig. 2, a view similar to Fig. 1, illustrating the door and other parts of the apparatus in their respective and relative positions when the door is in an intermediate position between the closing position and the position permitting entrance of the door into the guide frame;

Fig. 3, another similar view illustrating the door and other parts of the apparatus in their respective and relative positions when the door is in a position permitting movement of the carriage and door in the guide frame;

Fig. 4, another similar view illustrating the door and other parts of the apparatus in their respective and relative positions when the door has been moved to its extreme retracted position in the guide frame;

Fig. 5, an enlarged fragmentary transverse sectional view of parts of the apparatus in an intermediate position between the positions illustrated in Figs. 2 and 3, and in which the door may be hinged with respect to the carriage;

Fig. 6, an enlarged fragmentary view with portions in section looking in the direction of the arrows 6-6, Fig. 3, illustrating the releasable engagement of the door with the carriage;

Fig. 7, a detached view of the carriage looking in the direction of its upper end, and the tracks for the upper end of the carriage being indicated in their relative positions in dot and dash lines;

Fig. 8, another detached view of the carriage looking in the direction of its lower end, and the tracks for the lower end of the carriage being indicated in dot and dash lines;

Fig. 9, a fragmentary front elevation view of the safe when the door is in the closed position;

Fig. 10, an enlarged fragmentary view similar to Fig. 9 with portions broken away and illustrated in section;

Fig. 11, a fragmentary side elevation looking in the direction of the arrows 11-11, Fig. 10, with portions broken away and illustrated in section; and

Fig. 12, a fragmentary side elevation similar to Fig. 11 illustrating the several parts

of the apparatus when the door is in its extreme retracted or disappearing position within the guide frame.

Similar numerals refer to similar parts throughout the drawings.

The novel disappearing door structure or apparatus of the present invention is illustrated in the drawings as embodied in a heat resisting safe indicated generally at 10, and which may include walls forming an inner compartment indicated generally at 11, a monolithic heat and fire resisting shell indicated generally at 12 and enclosing the compartment 11, the shell being preferably provided with tension re-enforcing means indicated generally at 13, and the shell and compartment being enclosed in an external metallic case indicated generally at 14.

The front wall of the safe as illustrated is in the form of a door frame 15 having a doorway 16 formed therein.

A door indicated generally at 17 is mounted in the novel manner hereinafter set forth in detail for swinging movement to and from closing position in the doorway, and the inner side, top, and bottom faces of the door frame and the outer side, top, and bottom faces of the door are preferably tongued and grooved with each other as illustrated, for interfitting with each other when the door is swung to closing position, whereby when the door is closed there is no direct passageway for heat or flames to the interior of the compartment 11 between the door and the door frame.

The tonguing and grooving of the door and door frame may be of any usual arrangement, and the door may be provided with any usual bolt-work indicated generally by 18, and controlled in a usual manner by a lock 19, which may be a combination lock 19.

At one side of the safe preferably parallel with the side wall 20 thereof and at right angles to the front wall or door frame 15, a door carriage guide frame indicated generally by 21 extends preferably from the corner junction of the door frame 15 with the side wall 20.

The carriage guide frame 21 extends rearwardly from the door frame 15, and a door receiving opening 22 is formed in the front end wall 23 of the guide frame.

The guide frame 21 includes an upper horizontal guide track 24 and a lower horizontal guide track 25 extending parallel with each other and rearwardly from the front end wall 23 of the frame.

A door supporting carriage indicated generally by 26 is roller mounted for movement in the guide frame from the front end to the rear end thereof, as by means of laterally and longitudinally spaced upper rollers 27 mounted for rotation about vertical axes on the upper end of the carriage 26 and rolling on opposite sides of the upper track 24, and

a lower roller 28 mounted for rotation about a horizontal axis on the lower end of the carriage 26 and rolling on the top of the lower track 25.

5 The lower roller 28, rotating about its horizontal axis, supports the vertical component of the load applied upon the carriage 26, and transmits the vertical component to the top of the lower track 25.

10 The upper rollers 27, rolling against the opposite sides of the upper track 24, prevent twisting and lateral movement of the upper end of the carriage; and for preventing twisting and lateral movement of the lower end

15 of the carriage, laterally and longitudinally spaced lower rollers 29 are mounted for rotation at one side of the lower end of the carriage 26, and a secondary track 25' is located in the frame 21 and laterally spaced from

20 the track 25 and the lower rollers 29 roll against opposite sides of the tracks 25 and 25'.

The door 17 preferably includes sheet metal walls forming an outer shell 30, the interior 25 of which is filled with heat resisting material 31 and tension re-enforcing 32, and the front wall 33 of the shell 30 extends beyond the tongued and grooved side face 34 of the door adjacent the guide frame and when the door 30 is in closed position the front wall 33 extends across and closes the door receiving front end opening 22 of the guide frame.

The door 17 is supported by and mounted for swinging on the carriage 26 preferably 35 by double hinge means indicated generally at 35, and when the carriage is at the front end of the guide frame, the door is adapted for swinging movement to and from closing position in the doorway.

40 A latch-device 35' mounted on the carriage 26 is employed to latch the door to the carriage and in the plane of the carriage. This latch is automatic in the latching action immediately after the carriage starts to move 45 rearwardly; and the latch is automatically released as the carriage approaches the forward end of its movement, thus freeing the door from the latch and permitting it to be swung to closed position.

50 Novel adjustable tension means for maintaining the carriage in door sustaining position, that is, preventing racking of the carriage under the weight of the heavy door, are indicated generally at 36, and the tension means preferably include a flexible member 37 which may be a chain as illustrated, and the upper end 37a of the flexible member 37 is connected to the upper end of the carriage 26, and the lower end 37b of the flexible member 37 is connected to the lower end of the carriage 26.

55 Means for sustaining and guiding the load applied to the flexible member 37 are provided preferably by sprocket rollers 38a, 38b, and 38c; and the sprocket roller 38a is mount-

ed for rotation at the upper rear portion of the frame 21; and the sprocket rollers 38b and 38c are spaced from each other longitudinally of the tracks; and the sprocket 38b is mounted for rotation at the rear lower portion of the frame 21; and the sprocket 38c is mounted for rotation at the forward lower portion of the frame 21.

70 The flexible member passes rearwardly from its upper end 37a about the upper roller 38a, and thence downwardly about the lower roller 38b, and thence forwardly about the lower roller 38c, and thence upwardly and rearwardly to the connection of its lower end 37b with the lower end of the carriage.

75 For adjusting the tension of the flexible member 37, a turnbuckle 39 is preferably interposed in the flexible member preferably between the sprocket roller 38a and the sprocket roller 38b.

80 Each latch means 35' may include as illustrated a latch arm 40 mounted for rotation about a horizontal axis as on a pivot screw 41 passing through a suitable bearing aperture in the upper end of the arm 40 and screwing into the carriage 26.

85 Spring means 42 yieldingly urge the lower end of the latch arm 40 towards the front of the guide frame, and a stop 43 may be provided for limiting the forward movement of the latch arm.

90 Spring means 42 yieldingly urge the lower end of the latch arm 40 towards the front of the guide frame, and a stop 43 may be provided for limiting the forward movement of the latch arm.

95 When the door is swung from the open position to the position illustrated in Figs. 3 and 6, the latch means 35' each releasably engage the door with the carriage in position 100 permitting entrance of the door through the door receiving opening 22 into the guide frame.

100 Means are provided which operate to release the latch means 35' from position engaging the door and the carriage when the carriage is moved to a predetermined forward position, and the latch releasing means may each include a stop tongue 44 secured at the front of the guide frame 23 for being abutted by a pin 45 on the cooperating latch arm 40 when the carriage is moved to its extreme forward position as illustrated in Figs. 5 and 11.

105 Means are provided for limiting the forward movement of the carriage 26 and may include a tongue 46 depending from the bottom face at the rear of the door wall 33 and movable for abutment against a stop 47 extending upwardly from the bottom of the guide frame 21.

110 The improved apparatus as thus broadly set forth is adaptable for any type of door, but for facilitating seating of the tongued and grooved door 17 into the tongued and grooved door frame 15, the novel double hinge means 35 cooperate with hinge pins 48 mounted at the upper and lower ends of the carriage side of the door frame 15 in the position ordinarily occupied by ordinary hinge pins, and

each hinge pin 48 cooperates with a rearwardly opening bearing slot 49 formed in a bracket 50 mounted on the wall 33 of the door between the door shell and the carriage.

5 The double hinge 35 and the cooperating pin 48 and pivotal-bearing 49, as well as other details of construction illustrated herein, but not further described or claimed, comprise the invention of Albert L. Abbott, William C. Miller, and Charles E. Miller, and will be set forth in a companion application for Letters Patent.

10 The present invention, while particularly adapted for use in safes as aforesaid for attaining the above set forth objects, is broadly adapted for use wherever it is desired to support a ponderous member such as a door or the like on a carriage mounted for translatory movement in a guide frame.

15 The present invention furthermore preferably includes protective means for preventing the fingers of an operator of the improved disappearing door safe 10 from being caught between the hinge side of the front wall 33 and front end opening 22 of the guide frame 20.

20 The protective means may include a secondary closure member 60 which is hinge mounted and spring-held on the wall 33 preferably between the door shell and the carriage, and which extends over the door receiving opening 22 of the guide frame 25.

25 The operation of the secondary closure member 60 is best understood in Figs. 1, 2 and 5. The member is spring-held in the position shown in Fig. 1, but yields as shown in Fig. 2 in the operation of opening the door. It will be understood that the member 60 serves as a guard to prevent the fingers of 30 any person standing near being accidentally caught between the rear end of the extension of the plate 33 and the wall 23 at the front end of the frame in which the door is housed after it is opened. When the door is in the 35 closed position shown in Fig. 1, the rigid extension of the plate 33 covers the opening at front end of the guide-frame, and the hinged guard 60, lies adjacent the front wall 28 shown in Figs. 1 and 2.

40 Referring to Figs. 11 and 12, it will be understood that when the door is shoved rearwardly into the guide-frame, the tension chain 36 has a compensating movement which permits this action, but nevertheless 45 serves to hold the mullion 26, accurately in upright position. As has been stated, the weight of the door tends to tilt the carriage forwardly, but the tension chain counteracts or counter-balances this tendency.

50 The foregoing detailed description has been given for clearness of understanding only and no unnecessary limitations should be understood therefrom but the appended claims should be construed as broadly as 55 permissible in view of the prior art.

We claim:

1. Apparatus for disappearing doors and the like including a door frame having a doorway formed therein, a carriage guide frame extending from and angular to the 70 door frame adjacent one side of the doorway, the guide frame having a door receiving opening formed therein and spaced from the doorway, a carriage mounted in the guide frame for movement towards and away from the door frame, a door mounted on the carriage and movable between closing position in the doorway and a position in alignment with the door receiving opening of the guide frame, permitting movement of the door into 80 the guide frame, means maintaining the carriage in door sustaining position, and a rigidly carried wall on the door extending across and forming a closure for the door receiving opening when the door is in closed position in 85 the doorway.

2. In means of the character set forth: a safe-structure having its front wall provided with a door frame and having lateral walls extending rearwardly from the plane of said door frame and having a carriage frame outside of and adjacent one lateral wall, said carriage frame having a track extending between the planes of the front and rear walls of the structure; a carriage mounted to travel forwardly and rearwardly on said track, said carriage comprising an upright mullion; a door swingingly mounted on said mullion, adapted to be swung from closed position to the plane of the carriage frame, and vice versa, when the mullion is at the front end of its traverse; and a carriage-controlling device connecting said carriage and said frame, said device including flexible connecting means and supports therefor near the front and rear ends of the traverse of said mullion, said device serving to hold said mullion in true upright position, regardless of the position of said carriage on said track.

3. A structure as defined in claim 2, in 110 which said flexible connecting means comprises a chain and said supports comprise pinions engaging said chain and journaled on the carriage frame at points near the front and rear ends of traverse of said mullion.

4. A structure as specified in claim 2, in 115 which said flexible connecting means comprises a chain having its ends secured to the upper and lower end portions of said mullion, and said supports comprise pinions mounted 120 on the carriage frame, one at the lower front portion of said frame, one at the lower rear portion of said frame, and one at the upper rear portion of said frame.

5. A structure as specified in claim 2, in 125 which said flexible connecting means and said supports are disposed in a plane outside of and parallel with the plane in which said mullion travels.

6. In means of the character set forth: a 130

safe-structure having its front wall provided with a door frame and having lateral walls extending rearwardly from the plane of said door frame; a closed chamber outside of and parallel with one end-wall of the safe-structure, constituting a carriage-frame equipped with a track, said chamber having at its front wall a vertical opening; a carriage mounted on said track, comprising an upright mullion adapted to travel forwardly and rearwardly in said chamber; a door swingingly mounted on said mullion and movable through said opening, said door having a rigid extension adapted to form a closure for the opening and a carriage-controlling device connecting said carriage and frame, said device including flexible connecting means having its ends secured to the upper and lower portions of said mullion, and supports therefor journaled on said frame, said supports being disposed, one at the lower front corner, one at the lower rear corner, and one at the upper rear corner of said frame.

7. A structure as specified in claim 6, in which the flexible connecting means and the supports therefor are located within the chamber outside of the plane of traverse of said carriage.

8. In a structure of the character set forth: a guide-frame provided with a track; a carriage movable on said track comprising an upright mullion; a door swingingly mounted on said mullion, adapted to swing from a position in the plane of said guide-frame to a position at right angles thereto, and vice versa, when said carriage is at the forward end of its traverse; and a carriage-controlling device located at one side of the plane in which said carriage travels connecting said carriage and frame, said device including flexible connecting means and supports therefor near both ends of the path traversed by said carriage, said supports permitting compensating movement of said flexible means as the carriage travels.

9. In means of the character set forth: a safe-structure having a front wall provided with a door frame and having lateral walls extending rearwardly from the front wall; a carriage guide frame disposed outside of and parallel with one lateral wall of said structure; a carriage mounted in said guide-frame for forward and rearward movement therein; a door swingingly mounted on said carriage and movable between closing position in said door frame and a position in the plane of said carriage guide-frame; and releasable latching means for latching the door and the carriage together in position permitting movement of the door into the guide-frame.

10. A structure as specified in claim 9, in which the door is provided with a rigid extension projecting beyond the door-supporting hinges, and in which said releasable

means comprises a latch mounted on said carriage and adapted to engage said extension to secure the door and carriage together in a plane permitting a retreating movement of said door.

11. A structure as specified in claim 9, in which said releasable means for latching the door and carriage together comprises a latch mounted on said carriage, and means for automatically actuating said latch.

12. A structure as specified in claim 6, in which a guard member is hinged to the rigid extension of said door and projects beyond the free vertical edge thereof when the door is in closed position.

In testimony that we claim the above, we have hereunto subscribed our names.

ALBERT L. ABBOTT.
WILLIAM C. MILLER.
